(57) **CLAIM**

The ornamental design for a caddy for positive airway pressure breathing device, as shown and described.

DESCRIPTION

FIG. 1 is a front perspective view of a caddy for positive airway pressure breathing device showing our new design in a sample environmental setting;

FIG. 2 is an enlarged perspective view thereof, showing the caddy in isolation;

FIG. 3 is a reverse perspective view thereof;

FIG. 4 is a right elevation side view thereof;

FIG. 5 is a left side elevation view thereof;

FIG. 6 is a top plan view thereof;

FIG. 7 is a bottom plan view thereof;

FIG. 8 is a rear elevation view thereof;

FIG. 9 is a front elevation view thereof; and,

FIG. 10 is a bottom perspective view thereof.

One or more views (e.g., bottom view) may not be shown as those views are unornamented or simply not claimed in a given embodiment.

The broken lines show portions of the design that form no part of the claimed design.

The stippled shading (in FIGS. 4, 5 and 7) represents a different material compared to the material represented by line shaping.

1 Claim, 6 Drawing Sheets
